CLAIM

The ornamental design for an electronic cigarette, as shown and described.

DESCRIPTION

FIG. 1 is a bottom perspective view of a first embodiment of an electronic cigarette showing my new design;

FIG. 2 is a front elevational view thereof;

FIG. 3 is a back elevational view thereof;

FIG. 4 is a left elevational view thereof, the right side being a mirror image;

FIG. 5 is a top plan view thereof;

FIG. 6 is a bottom plan view thereof;

FIG. 7 is a bottom perspective view of a second embodiment of an electronic cigarette showing my new design;

FIG. 8 is a front elevational view thereof;

FIG. 9 is a back elevational view thereof;

FIG. 10 is a left elevational view thereof, the right side being a mirror image; and

FIG. 11 is a top plan view thereof; and,

FIG. 12 is a bottom plan view thereof.

In the drawings, the broken lines depict portions of the electronic cigarette that form no part of the claimed design.

1 Claim, 6 Drawing Sheets
